(57) **CLAIM**

The ornamental design for a umbrella supporting device, as shown and described.

DESCRIPTION

FIG. 1 is a front elevational view of an umbrella supporting device showing my new design;
FIG. 2 is a rear elevational view thereof;
FIG. 3 is a right side elevational view thereof;
FIG. 4 is a left side elevational view thereof;
FIG. 5 is a top plan view thereof;
FIG. 6 is a bottom plan view thereof;
FIG. 7 is a partially enlarged view of FIG. 1;
FIG. 8 is a partially enlarged view of FIG. 2;
FIG. 9 is a partially enlarged view of FIG. 3;
FIG. 10 is a partially enlarged view of FIG. 4;
FIG. 11 is a partially enlarged view of FIG. 6; and,
FIG. 12 is a partially enlarged top plan view of FIG. 1.
